UNITED STATES PATENT OFFICE.

AUGUST BOSTROEM, OF NEW YORK, N. Y., ASSIGNOR TO SAMUEL ROBERT SCHWARTZ,
OF NEW YORK, N. Y.

DESIGN FOR A PORTABLE LAMP BASE.

61,362.

Specification for Design.

Patented Aug. 15, 1922.

Application filed December 22, 1921. Serial No. 524,311. Term of patent 7 years.

To all whom it may concern:

Be it known that I, AUGUST BOSTROEM, a citizen of the United States of America, residing at New York, in the county of Bronx and State of New York, have invented a new, original, and ornamental Design for a Portable Lamp Base, of which the following is a specification, reference being had to the accompanying drawing, forming part thereof.

Figure 1 is a perspective view showing my new design.

Figure 2 is a plan view and

Figure 3 is a view showing the application

of a base according to my new design to a portable electric lamp.

I claim:

The ornamental design for a portable lamp base, as shown.

In testimony whereof, I have signed my name to this specification in the presence of two subscribing witnesses, this twenty-first day of December, 1921.

AUGUST BOSTROEM.

Witnesses:

POLLY BARTELS,
OLGA ROSENBERG.
